PAGE 3

Fig. 1 is a plan view in perspective of the gasoline engine unit for chain saws embodying our new design;

Fig. 2 is a view in perspective from the fan side of the machine;

Fig. 3 is another view in perspective from the fan side of the machine;

Fig. 4 is a view in perspective from the carburetor side of the machine.

The fragmentary disclosure of the chain saw disclosed in broken lines is shown for illustrative purposes only.

We claim:

The ornamental design for a gasoline engine unit for chain saws, as shown and described.
